DESIGN FOR A COMBINATION UNDERGARMENT

Joseph A. Rielly, Forest Hills, N. Y.

Application March 25, 1938, Serial No. 76,097

Term of patent 14 years

To all whom it may concern:

Be it known that I, Joseph A. Rielly, a citizen of the United States and a resident of the city of New York (Forest Hills, Borough of Queens), in the county of Queens and State of New York, have invented a new, original, and ornamental Design for a Combination Undergarment, reference being had to the accompanying drawing, forming part thereof, in which

Fig. 1 is a front view of a combination undergarment showing my new design; and

Fig. 2 is a rear view of the garment shown in Fig. 1.

The essential feature of my design resides in the specific tubular center portion in combination with the flared upper and lower portions of the combination undergarment, as shown.

I claim:

The ornamental design for a combination undergarment, substantially as shown and described.

JOSEPH A. RIELLY.
